EXERCISING DEVICE

Roosevelt W. W. Harvey, Somerville, Mass.

Application March 10, 1948, Serial No. 14,103

2 Claims. (Cl. 272—84)

1

This invention relates to an exercising device. The invention has for an object to provide a novel and improved exercising device particularly adapted for developing the arm muscles and other parts of the body and which is characterized by novel and efficient structure capable of adjustment as to leverage to vary the effective weight of the device when lifted with one end used as a fulcrum.

With this general object in view and such others as may hereinafter appear the invention consists in the exercising device hereinafter described and particularly defined in the claims at the end of this specification.

In the drawings illustrating the preferred embodiment of the invention, Fig. 1 is a side elevation of an exercising device embodying the present invention; and Fig. 2 is a longitudinal sectional view of the same.

In general, the present invention contemplates an exercising device which may be termed a leverage bar and which is particularly adapted for development of the arms, chest and other muscles of the body. The illustrated exercising device comprises, in general, an elongated bar which may be grasped at spaced points at one end of the bar and having a weight adjustably mounted thereon at the second end. In use, one end of the bar is grasped in one hand and used as a fulcrum and the bar is lifted with the other hand grasping an intermediate portion of the bar, the bar being moved substantially radially to swing the weighted end through an arcuate path. Thus, when the weight is adjusted toward the fulcrum end of the bar the force required to swing the weighted end upwardly is less than the force required when the weight is adjusted outwardly toward the opposite end of the bar.

Referring now to the drawings, the illustrated leverage bar comprises an elongated rod or bar 10 having a pair of spaced handles or grips 12, 14 mounted thereon near one end of the bar and a weighted unit, indicated generally at 16, mounted at the other end of the bar to be capable of adjustment longitudinally of the bar.

In practice, the grip 12 may be placed at the fulcrum end of the rod, and the grip 14 may and preferably will be spaced from the grip 12 a distance approximating the distance between the shoulders so that when grasped with the arms extending downwardly from the shoulders the hands will be positioned in alignment with the grips. The grips may be conveniently made from fibre tubing or other suitable similar material and the endmost grip 12 may and preferably will be

2

fast on the end of the bar, the fibre tube being of a size so that it may be pressed onto the bar in friction tight relation. The other grip, 14, is preferably rotatably mounted on the bar so that when the unit is grasped and lifted through an arc the grip 14 may rotate with the hand relative to the bar. As herein shown, the grip 14 may be provided with a corrugated or other suitable gripping surface and is held from longitudinal displacement on the bar by collars 18, 20 at the ends thereof, the collars being secured to the bar by welding or in other suitable manner. The weighted unit 16 may comprise a circular disc or plate 21 carried by a sleeve portion 22 extending from and formed integrally with a collar 24 slidably mounted on the bar and having a set screw 26 therein for securing the weighted unit in its longitudinally adjusted position on the bar. The disc weight 21 is placed against the shoulder formed by the collar 24 of the sleeve and is clamped in place by a second collar 28 adjustably movable on the sleeve and secured thereto by a locking screw 30.

As herein shown, the rod or bar 10 is provided with spaced graduations 32 indicating the approximate effective weight lifted when the bar is pivoted at the fulcrum end in one hand and lifted or swung through an arc by the other hand and with the weighted unit 16 adjusted on the bar at a particular graduation. In practice, I have found the preferred proportions of a leverage bar made up in accordance with the present invention to be as follows: The length of the bar 10 may be about four and one half feet overall; the distance from center to center of the hand grips 12, 14 may be between eighteen and twenty-one inches, corresponding to the average distance between the shoulders; the leverage bar assembled, without the disc weight 21 may weigh about eight pounds; and the disc weight itself may weigh ten pounds.

With these proportions when the disc weight 21 is assembled on the sleeve and the weighted unit 16 is adjusted on the bar to its innermost extent up against the handle 14, the force required to swing the bar through an arc, as described, will be about twenty pounds, and adjustment of the weight 16 a distance of about one and one-half inches away from the end of the grip 14 will change the leverage so as to require a force of twenty-one pounds to lift the bar through the arcuate path. Further adjustment outwardly at two and one-eighth inch spaced intervals will each increase the effective leverage about one pound, the illustrated leverage bar having provision for increasing the effective weight

up to thirty-five pounds. It will be observed that the sleeve 22 is extended to provide space for additional discs 21 of various weights to proportionately increase the leverage and effective weight of the bar when used as described. It will be understood that the above specified proportions are given only by way of example and may be varied without departing from the invention.

In using the present exercising unit, the bar is grasped at the grips 12, 14 by both hands with the user in a standing position and with one arm extended and the hand acting as a fulcrum for the end of the bar, the weighted end is lifted with the other arm through an arcuate path, this exercise being repeated as long as desired. The position of the rod may then be reversed with the opposite hand acting as a fulcrum and the lifting performed with the other arm.

An advantage in using the present leverage bar is that a beginner may start his training by lifting a bar with the weight adjusted for a relatively low leverage or effective weight, and, as his training is advanced he may progressively increase the leverage each practice period by outward adjustment of the weight. When the limit of the leverage is reached with one weight, additional discs may be added to further increase the weight to be lifted.

While the preferred embodiment of the invention has been herein illustrated and described it will be understood that the invention may be embodied in other forms within the scope of the following claims.

Having thus described the invention, what is claimed is:

- 4
- 10 5. 1. An exercising device of the character described comprising an elongated bar, a pair of spaced hand grips at one end of the bar comprising an endmost hand grip fixed to the bar and adapted for use as a fulcrum, and an intermediate hand grip by which the unit is lifted through an arcuate path, said intermediate hand grip being concentrically rotatably mounted on the bar, and a weight mounted upon the second end of the bar and capable of adjustment longitudinally thereof.
- 15 2. An exercising device of the character described comprising an elongated bar, a pair of spaced hand grips mounted upon one end of the bar, and a weighted member mounted for longitudinal adjustment at the other end of the bar; said weighted member comprising a sleeve slidably mounted on the bar, a weight removably mounted on the sleeve, means for clamping the weight to the sleeve, and means for securing the sleeve in its adjusted position along the bar.
